CHILD'S CRIB OR BASSINET

Filed July 26, 1928

UNITED STATES PATENT OFFICE

WALTER L. BEAMAN, OF GARDNER, MASSACHUSETTS, ASSIGNOR TO GEM CRIB & CRADLE COMPANY, OF GARDNER, MASSACHUSETTS, A CORPORATION OF MASSACHUSETTS

CHILD'S CRIB OR BASSINET

Application filed July 26, 1928. Serial No. 295,591.

This invention relates to a child's crib or bassinet.

One object of my invention is to improve the supporting structure of such an article, to the end that it may be more easily guided and moved from place to place. A further object is to improve the method of assembling and securing the several parts of the article together, to the end that the crib or bassinet 10 may be more economically constructed and that a wider range of design may be made available.

My invention further relates to arrangements and combinations of parts which will be hereinafter described and more particularly pointed out in the appended claim.

A preferred form of the invention is shown in the drawings in which

Fig. 1 is a perspective view of a bassinet 20 embodying my improvements;

Fig. 2 is an enlarged side elevation of the supporting structure or running gearing therefor;

Fig. 3 is a partial end elevation of the bassinet; and

Fig. 4 is a detail sectional view, taken along the line 4—4 in Fig. 3.

Referring to the drawings, I have shown a crib or bassinet having a body or frame 10, 30 supported on wheels 11 and 12.

It has been previously customary to provide such bassinets with four wheels, all mounted to rotate about fixed horizontal axes, or with four wheels all of which were mounted on bearings which were swiveled or movable about separate vertical axes. Where the wheels are all supported on fixed axes, the bassinet will roll in a straight path only, and in turning a corner or rounding a curve, it has been necessary to partly raise and bodily displace one end of the bassinet laterally.

In the type of bassinet having four swiveled wheels, it has been found very difficult to cause the bassinet to travel in a desired direction, as the provision of four wheels movable about independent vertical axes causes the bassinet to travel erratically and in entirely unexpected directions.

I have discovered that the disadvantages 50 of these two prior constructions may be en-

tirely eliminated by mounting the wheels 11 at one end of the bassinet to rotate about a fixed horizontal shaft or axle 13, and by mounting the wheels 12 at the other end of the bassinet to rotate in brackets 15, which in turn are supported in bearings 16, secured to the frame 10. The brackets 15 are therefore free to move about independent vertical axes, while the wheels 12 rotate about independent horizontal axes.

If a bassinet thus equipped is propelled with the wheels 11 at the front, it may be caused to travel in any direction and may be diverted from a straight line by pushing the bassinet sidewise without disengaging any of the bassinet wheels from the floor. A vehicle thus supported is therefore more easily moved from place to place.

In constructing the frame or body of a bassinet it has been the previous practice to provide panels in the sides or ends, which panels have been framed or mortised into the upper and lower rails, a somewhat expensive construction and one which does not adapt itself readily to variations in design.

In my improved bassinet, I have provided the usual slats 20, framed into the upper and lower rails 21 and 21^a in spaced relation, and I have provided an additional member 22 which may be a panel of an ornamental outline and which is secured to the side or end of the bassinet by fastening said member directly to the outer faces of the slats 20. The member 22 may be thus secured by nails or screws 23, or may be glued or cemented to the slats 20, and for greater security both of these methods of attachment may be used.

As the member or panel 22 is secured to the slats 20 after the slats and frame members are assembled, and as the member 22 is not mortised or otherwise inserted in the frame, it will be evident that the member 22 may be widely varied in outline and design and that bassinets may be framed up in quantity and thereafter receive different members 22, thus producing a varied line of designs upon a single stock foundation frame.

Furthermore the range of design is very much greater than with the previous construction in which the panels were framed

into the upper and lower rails and were consequently not capable of any very wide variation in design.

Having thus described my invention and the advantages thereof, I do not wish to be limited to the details herein disclosed, otherwise than as set forth in the claim, but what I claim is:—

A crib or bassinet comprising a body having a plurality of vertically disposed slats forming an enclosure, horizontal bars morticed to receive the upper and lower ends of said slats, a panel secured to and supported entirely by said slats, and effective as a bracing and rigidifying element, said panel directly engaging the outer faces of said slats and abutting the under side of the upper cross bar, and said panel being provided with fastening devices by which the panel is permanently and securely attached to the slats and in direct contact therewith.

In testimony whereof I have hereunto affixed my signature.

WALTER L. BEAMAN.
